DESIGN FOR A RECEPTACLE FOR CIGARETTES OR THE LIKE

Thomas R. Goldberg, New York, N. Y.

Application August 30, 1940, Serial No. 94,727

Term of patent 3½ years

To all whom it may concern:

Be it known that I, Thomas R. Goldberg, a citizen of the United States and a resident of the city of New York, Borough of Manhattan, county and State of New York, have invented the new, original, and ornamental Design for Receptacle for Cigarettes or the like, of which the following is a specification, reference being had to the accompanying drawing, forming part thereof, in which—

Figure 1 is a perspective view of a receptacle for cigarettes or the like embodying my design;

Fig. 2 is a side elevation of the receptacle, the other side of the receptacle being a mirror image of the side shown; and

Fig. 3 is a front elevation of the receptacle.

I claim:

The ornamental design for a receptacle for cigarettes or the like, substantially as shown.

THOMAS R. GOLDBERG.
